UNITED STATES PATENT OFFICE.

ANDREW S. CAIRNCROSS, OF ST. PAUL, MINNESOTA.

AUTOMATIC STOP MECHANISM FOR ROTARY OVENS.

No. 831,829.

Specification of Letters Patent.

Patented Sept. 25, 1906.

Application filed April 7, 1905. Renewed August 23, 1906. Serial No. 331,771.

To all whom it may concern:

Be it known that I, ANDREW S. CAIRNCROSS, a citizen of the United States, residing at St. Paul, in the county of Ramsey and 5 State of Minnesota, have invented certain new and useful Improvements in Automatic Stop Mechanism for Rotary Ovens, of which the following is a specification.

My invention relates to improvements in 10 automatic stop mechanism for rotary ovens; and it consists in improved mechanism for stopping the rotation of the oven at predetermined intervals.

To this end my invention consists in the features of construction and combination herein- 15 after particularly described and claimed.

In the accompanying drawing, which shows a front elevation of my invention in connection with an oven, A represents the outside 20 casing of the oven. Within the casing and mounted upon the shaft 2 is a rotary oven 28 for holding cookies or other articles. Secured upon the outer end of the shaft 2 is a worm-wheel 3, with which intermeshes a worm 4, 25 mounted upon the horizontal driving-shaft 5. The shaft 5 has suitable journal-bearings 6 and carries a loose pulley 7 and fixed pulley 8, adapted to be connected by a belt (not shown) with a suitable source of power.

30 The belt is adapted to be shifted from the fixed to the loose pulley and the driving-shaft stopped by the following described mechanism: Slidably mounted in bearings 9, parallel with the shaft 5, is a shaft 10, connected 35 at one end with a fixed bracket 11 by a spring 12. The shaft 10 carries a belt-shifter 13 of suitable construction. Having pivotal support 14 below the shaft 10 is a bent lever 15, the upper end of the bent lever engaging with 40 a boss 16, carried by the shaft 10, the opposite end of the bent lever having pivotal connection 17 with the lever-arm 18. The lever-arm 18 has fulcrum-support 19 and at its outer end carries a brake 20, which works in connec-

45 tion with a brake-pulley 27, mounted on the main driving-shaft 5, the opposite end of the lever-arm 18 carrying a roller 21, constructed to fit into recesses 22, formed in the outer edge of a ring 23, carried by the worm-wheel 50 3. The lever-arm 18 is connected at its worm end by a cable 24 with a foot-pedal 25, the cable running over suitable pulleys 26.

Operation: With the parts in the position shown in the drawing the operator to start 55 the rotation of the oven will depress the pedal 25, lifting the lever-arm 18 out of engagement

with the recessed ring 23. This slides the rod 10 by means of the intermediate bent lever 15, shifting the belt from the loose pulley 7 to the fixed pulley 8 and releasing the brake 60 20. The oven will now be rotated, the pulley 21 of the lever 18 traveling upon the outer edge of the ring until it reaches the succeeding recess 22. As the roller reaches the succeeding recess it will be carried into it through 65 the medium of the spring 12, which withdraws the slidable rod 10, carrying the belt-shifter 13 from the fixed to the loose pulley and acting upon the lever-arm 18 through the connecting bent lever 15. This movement 70 of the lever-arm 18 will set the brake 20, carried by the opposite end of the lever-arm, against the brake-pulley 27 to stop rotation of the oven. When it is desired to again start the rotation of the oven, the operator 75 80 simply has to depress the pedal 25. The rotation of the oven is thus automatically stopped at predetermined intervals, the length of the intervals being regulated by the distance between the recesses 22 of the ring 23.

Having now described my invention, what I claim as new, and desire to secure by Letters Patent, is—

1. In combination with a rotary supporting-shaft of the class described, a main driving-shaft, operative connection between said shafts, a ring with peripheral recesses carried by said supporting-shaft, a pivotally-supported lever arranged in position to coöperate with said recesses, braking means carried by said lever in position to brake said main driving-shaft, means for actuating said lever to throw the same into braking position, and means actuated by said lever for simultaneously throwing said driving-shaft out of 95 operation.

2. In combination with a rotatable supporting-shaft of the class described, a main driving-shaft, operative connection between said shafts, a ring carried by said supporting-shafts and provided with peripheral recesses, a pivotally-supported lever arranged in position to coöperate with said recesses, braking mechanism supported by said lever in connection with said main shaft, a slidable spring-actuated rod supported adjacent to said main shaft, a belt-shifter carried by said rod, and a connection between said lever and slidable rod, for the purpose set forth.

3. In combination with a rotatable supporting-shaft of the class described, a main driving-shaft, operative connection between

said shafts a ring carried by said supporting-shaft and provided with peripheral recesses, a pivotally-supported lever provided at one end with a roller fitted to said recesses and at 5 the other end with a brake arranged in position to coöperate with the main shaft, a slideable spring-supported rod arranged adjacent to said main shaft, belt-shifting mechanism carried by said slideable rod, and a crank-arm

connecting said lever with said slideable rod, 10 for the purpose set forth.

In testimony whereof I affix my signature in presence of two witnesses.

ANDREW S. CAIRNCROSS.
